UNITED STATES PATENT OFFICE.

EARL T. BENNINGTON, OF WILLOUGHBY, OHIO, ASSIGNEE TO THE CLEVELAND CRANE AND ENGINEERING COMPANY, OF WICKLIFFE, OHIO, A CORPORATION OF OHIO.

CRANE.

Application filed March 14, 1923. Serial No. 624,939.

To all whom it may concern:

Be it known that I, EARL T. BENNINGTON, a citizen of the United States, residing at Willoughby, in the county of Lake and State of Ohio, have invented a certain new and useful Improvement in Cranes, of which the following is a full, clear, and exact description.

This invention relates to cranes of the hand propelled electric hoist type, and has for its chief object to improve the control of cranes of this type so as to make it possible for an operator with one hand to move the crane along the runway and to move the trolley along the crane and to control the hoist without making it necessary for him to shift his hand from one point to another, and leaving his other hand free for other work.

20 In carrying out my invention a rigid pipe is extended downward from the trolley far enough so that it can be conveniently reached by the operator while standing on the floor, this pipe being connected to the 25 trolley in a manner such that the operator can, by pushing or pulling on it either move the trolley along the crane, or the crane along its runway. The trolley is provided with an electric hoist which is remote controlled, and for the control of the hoist switching means preferably in the form of a pair of push button switches are provided near the bottom of the pipe which forms a conduit for the switch wiring, so that the 30 operator can with his thumb operate either of the hoist controlling switches while his hand grips the pipe to shift the crane or trolley, or both.

The invention may be further briefly summarized as consisting in certain novel details of construction, and combinations and arrangements of parts which will be described in the specification and set forth in the appended claims.

45 In the accompanying sheets of drawings wherein I have shown the preferred embodiment of the invention, Fig. 1 is a perspective view showing a portion of a crane and one of the runway rails for the crane, said 50 crane being equipped with my invention; Fig. 2 is a side view of the trolley and of a portion of the body of the crane. Fig. 3 is an enlarged view of the lower end of the crane controlling member showing the push

button hoist control switches and illustrating also the fact that the hollow control member constitutes a conduit for the wires leading from the push button switches; and Fig. 4 is a wiring diagram for the motor and the remote controlled and push button switches.

The crane herein illustrated is in itself of the well-known type which has a body or cross-portion 10 in the form of an I-beam, to the ends of which are connected end trucks 11 having wheels 12 which travel along the parallel rails 13 of the crane runway. I have herein illustrated simply one of the rails 13 and one of the wheeled end trucks 11, but it will be understood that the construction at both ends is the same except that the truck at one end of the crane has a pair of current collectors.

Travelling over the lower flange of the I-beam 10 is a trolley 14 which is provided with an electric hoist. The details of the hoist are immaterial to my invention, but I have indicated the motor at 15, the cable drum at 16 on which the hoist or load cable 17 is adapted to be wound and from which it is designed to be unwound to raise and lower the load respectively.

The motor receives current from a pair of trolley wires 18 which are engaged by trolley wheels 19 carried by the trolley, these 25 trolley wires 18 extending across the crane above and parallel to the I-beam 10. They receive current from a pair of main trolley wires 20 which are above one of the runway rails 13 and are engaged by trolleys 21 carried by one of the end trucks 11 of the crane.

A crane of this type is pulled or pushed by hand along the runway, and the trolley is in a similar manner moved along the crane. In accordance with my invention the means for moving the crane or the trolley, or both, and the means for controlling the hoist is embodied more or less in one element, and with this in view I extend 100 down from the trolley a pipe 22 which has sufficient length that the lower part can be conveniently reached by the operator on the floor below. The upper part of the pipe is in any suitable way rigidly connected to the 105 trolley so that it extends down as a rigid arm or handle which will enable the trolley to be pushed along the crane and the crane

to be pushed along its runway. There are various ways in which the upper end of this pipe can be rigidly connected to the trolley for the purpose described, but in this instance its upper end is attached to an extension 23^a of a load bar 23 of the trolley, and a short distance beneath the load bar this pipe is connected to the trolley by a bracing member 23^b. In this manner sufficient rigidity is provided between the trolley and pipe for the purpose of moving the trolley and the crane. Heretofore it has been necessary in a crane of this type to position the load or trolley at the center of the crane before the crane could be moved along the runway, since by pushing against the load with the trolley near one end, that particular end would move but the other end would remain stationary, causing a binding action. However, I find that this objection can be overcome very effectively, i. e., that the crane can be moved along the runway by pushing or pulling on the pipe even though the trolley is near one end by flexibly suspending the runway and by providing on the end trucks supporting wheels which swivel so that the flanges of the wheels are prevented from digging into the rails and thus causing a binding action.

In accordance with my invention the hoist motor is remote-controlled through the medium of solenoid operated switches, the details of which are immaterial to my invention and which are preferably enclosed in a box 24 attached to one side of the hoist. In Fig. 4 I have shown conventionally or diagrammatically one way in which this can be accomplished. In this figure I utilize four remote controlled switches 25, 26, 27 and 28 which are closed by solenoids 29 adapted to be connected to the current supplying or line conductors 30 by switching means consisting preferably of push button switches 31 which in accordance with my invention are arranged in a housing 32 near the lower end of the pipe 22 as shown in Figs. 1 and 3. The wires, in this instance three in number, are extended up from the push button switches 31 through the pipe to a point near the upper end of the latter where they are extended inwardly to the box 24 containing the remote controlled switches.

Each of these push button switches controls two of the switches, one controlling the switches 25 and 27, and the other the switches 26 and 28. When one of the push button switches is closed so as to close two of the remote controlled switches, current passes from the line conductors 30 through the armature 15^a and field 15^b with the current passing through the armature in one direction, and when the switches of the other set are closed by manipulating the other push button switch, the current again passes through the field and armature of the motor

but through the armature in the reverse direction. In other words, when one push button switch is operated, the hoist cable is wound in so as to raise the load or load hook, and when the other push button switch is closed, the cable is unwound so as to lower the load or the load hook.

In practice, an interlock is provided between the two sets of remote controlled switches so that it is impossible to close all the switches at the same time, but as before stated, the details of the switches are immaterial to the invention; and the same is true of the interlock referred to, and hence it is not shown.

In moving the trolley or the crane itself, the operator puts his hand on the lower end of the pipe 22, and when he wishes to raise or lower the load he can do this by closing either push button switch with his thumb and without taking his hand from the pipe. He can thus move the crane or trolley and take care of the hoist with one hand without moving it from one point to another, and leaving the other hand free. In fact, with this one hand the several operations of moving the trolley and the crane, or both, and of controlling the hoist can be performed either simultaneously or successively.

While I have shown the preferred form of my invention, I do not desire to be confined to the exact details shown, but aim in my claims to cover all modifications which do not involve a departure from the spirit and scope of my invention as defined in the appended claims.

Having described my invention, I claim:

1. In combination with a crane adapted to be moved along a runway, a trolley adapted to be moved along the crane, an electric hoist in said trolley, and a rigid member extending down from the trolley and carrying hoist controlling switches.

2. In combination with a crane adapted to be moved along a runway, a trolley adapted to be moved along the crane and provided with an electric hoist, and a hollow crane and trolley moving member extending down from the trolley, and provided near its lower end with hoist controlling switches, said hollow member forming a conduit for the wires extending from the switches.

3. In combination with a crane adapted to be moved along a runway, a trolley adapted to be moved along the crane and provided with an electric hoist, remote controlled switches for operating the hoist, and a rigid member extending down from the trolley and provided near its lower end with hoist controlled switches connected to said remote controlled switches.

4. In combination with a crane adapted to be moved along a runway, a trolley adapted to be moved along the crane and provided with an electric hoist having remote con-

trolled switches, a rigid pipe connected to the trolley and extending downward therefrom, and a pair of hoist controlling switches near the lower end of said pipe, 5 said pipe constituting a conduit for wiring connecting the last mentioned switches to the remote controlled switches.

5. In combination with a crane runway, a crane movable by hand along the runway,

10 a trolley adapted to be moved by hand along the crane and having a motor operated hoist and a rigid member projecting down from the trolley and serving when force is applied thereto to move the trolley 15 along the crane or to move the crane along its runway or both, said member embodying means for controlling the hoist motor.

6. In combination with a load carrier adapted to be moved along an overhead 20 track, a hoist on said carrier by which the

load may be raised or lowered, a handle depending from the carrier by which said carrier may be pushed along the track, and means for operating the hoist, said hoist operating means including a controlling element, connected with the handle.

7. The combination with a load carrier adapted to be moved along an overhead trackway and having a hoist by which the load may be raised or lowered, of a member 30 depending from the carrier, said member having a connection with the carrier such that the carrier may be moved along the trackway when force is applied to said member, said member also having means by which the operation of the hoist may be controlled to raise or lower the load.

In testimony whereof, I hereunto affix my signature.

EARL T. BENNINGTON.
